UNITED STATES PATENT OFFICE.

HUBERT F. KRANTZ, OF BROOKLYN, NEW YORK, ASSIGNOR TO KRANTZ MANUFACTURING COMPANY, INC., OF BROOKLYN, NEW YORK, A CORPORATION OF NEW YORK.

MULTIPLE-UNIT SAFETY-SWITCHBOARD.

1,342,546.

Specification of Letters Patent.

Patented June 8, 1920.

Application filed August 2, 1917. Serial No. 184,011.

To all whom it may concern:

Be it known that I, HUBERT F. KRANTZ, residing at Brooklyn, in the county of Kings and State of New York, have invented certain new and useful Improvements in Multiple - Unit Safety - Switchboards, of which the following is a specification.

This invention relates to a multi-unit safety switch board.

10 The object of the invention is to provide a switch board comprising a plurality of independently operable switch units, each being mounted upon the board so that it may be readily inserted or removed, for repairs, or otherwise, without interfering with the operation of any of the other units.

A further object is to provide safety features in association with the respective units.

20 A more detailed object is to provide a switch board having bus bars traversing it and having a plurality of stalls or pockets formed adjacent the bus bars, and to provide independently operable switch units adapted to be arranged in said stalls in co-operative relation with the bus bars.

A further detailed object is to construct the switch units so that they provide a barrier intervening between a fuse compartment and the bus bars, and further, to provide a removable guard member for the fuse compartment, together with means for preventing removal of the guard member while there is current in any of the parts within the fuse compartment.

30 A further object is to provide improved means whereby the main line wires may be led into the bus bars, and whereby the branch line wires may be led in to the respective switch compartments or stalls, from various lateral directions, and further to provide simple means whereby the branch line wires may be exposed and readily lifted out of their appointed positions or facilitating such work thereon as may be required at any time.

40 A further object is to provide a new and improved mechanism associated with the switch blades for governing the operation thereof in accordance with the position of the guard member, and, inversely, to govern the position of the guard member in ac-

cordance with the position of the switch blades.

A further object is to provide means whereby a plurality of switch boards may be connected side by side in any number so as to comprise one large switch board made up of a plurality of sections, and to so construct the sections that ample wire channels are provided between adjacent sections through which channels the branch line wires may lead to the adjacent switch stalls at opposite sides of the channels, and further, to provide means whereby the main line bus bars may be properly and easily connected from one section to another.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings which are to be taken as a part of this specification, and in which I have shown merely a preferred form of embodiment of the invention:

Figure 1 is a rear elevational view of a switch board constructed in accordance with this invention.

Fig. 2 is a perspective view of the major portion of the switch board of Fig. 1 showing one of the switch units in position to be moved into its respective stall.

Fig. 3 is a rear elevational view of a part of the structure shown in Fig. 1, enlarged to show the details of construction of one of the stalls, together with the arrangement of parts of the switch unit in position therein, the guard members, or doors, for the stalls being removed and a portion of the switch unit being broken away and shown in section to better disclose its construction.

Fig. 4 is a vertical transverse sectional view taken substantially upon the plane of line IV of Fig. 3, the parts of the switch mechanism being shown in the "on" position and the door being shown closed.

Fig. 5 is a diagrammatic view of a por-

tion of the structure of Fig. 4 showing the position of the parts when the switch is in the "off" position, with the door yet closed.

Fig. 6 is a diagrammatic view showing 5 parts of Fig. 5 as they appear when the door is open.

Fig. 7 is a horizontal sectional view taken substantially upon the plane of line VII of Fig. 4.

10 Fig. 8 is a further enlarged fragmentary sectional view taken substantially upon the plane of line VIII of Fig. 4, the parts of the switch mechanism being in the "on" position.

15 Fig. 9 is a similar sectional view showing the parts of Fig. 8 with the switch mechanism in the "off" position and the door open.

20 Fig. 10 is a detail sectional view taken substantially upon the plane of line X of Fig. 9.

Fig. 11 is a detail perspective view of the connecting link which extends from the switch mechanism to the door.

25 Fig. 12 is a detail sectional view, similar to a portion of Fig. 4, but showing the manner in which certain portions of the switch mechanism may be disassembled when occasion arises.

30 Fig. 13 is a horizontal sectional view taken substantially upon the plane of line XIII of Fig. 12.

Fig. 14 is a horizontal sectional view 35 illustrating the manner of connecting a plurality of switch board sections together for completing one larger switch board.

Fig. 15 is a fragmentary detail sectional view illustrating a modification of the manner of mounting one of the fuse clips.

40 Referring to the drawings for describing in detail the particular structure which is illustrated therein, the reference character L indicates the main or base board or face plate. This may be made up of two separate layers as shown, for convenience and neatness in mounting the parts which are fixed thereto, or it may be made as a single plate, if desired.

Two sets of bus bars, as 1 and 2, are fixed 50 to the rear surface of the board or plate L, all in parallel relation and extending vertically of the plate.

At the opposite vertical edges of the plate are arranged branch line wire channels 3. 55 These extend approximately throughout the height of the plate and each is formed by a pair of wall members 4 and 5, which are arranged at right angles to the rear surface of the face plate spaced apart and connected 60 to the face plate by means of a bracket 6.

The brackets 6 may be fixed to the face plate in any suitable manner as by means of the bolts 7.

65 The forward vertical edges of the walls 4 and 5 are fixed to the outer surfaces of

the flanges of the brackets. The rear vertical edges of the walls 4 are formed with outwardly turned flanges 8 and the rear vertical edges of the walls 5 are formed with inwardly turned flanges 9 which lap 70 the flanges 8.

The walls 4 may be connected to the brackets 6 in any desired manner, as by the rivets 10. The walls 5 are intended to be removable at will when desired to give access 75 to the channels 3 and for this purpose they are preferably connected to the brackets 6 and to the flanges 8 by means of screws 11.

An intermediate partition wall 12 is also provided at the rear of the face plate, projecting at right angles to the face plate and substantially midway between the walls 4 and between the sets of bus bars 1 and 2.

80 The space between the partition wall and either of the walls 4 may be divided vertically by any number of horizontal partitions 13 so as to divide said space into a desired number of superposed pockets or stalls. In the drawing three such stalls are shown at each side of the partition wall. 90 Each stall is closed at the rear by a separate guard member or door G and each stall is adapted to removably contain an independently formed and independently operable switch unit. In Fig. 2 one such unit, as H, 95 is shown, detached and in position to be inserted in its respective stall.

The switch units each comprise a base plate or board 14. This board is preferably of insulating material, such as slate, 100 and when the unit is inserted into the stall, it stands substantially parallel with the rear surface of the face plate but spaced away from said surface so as to constitute a barrier within the stall for the bus bars so that 105 said bus bars may not be carelessly touched by an operator when the door is open. At the rear surface of the board or barrier 14 are arranged suitable fuse clips 15 and 16 for retaining fuses 17. At the forward face 110 are provided contact members 18 for the switch blades 19. The contact members 18 are arranged opposite to the adjacent main line bus bars, as 1, and there is, of course, one switch blade for each bus bar and one 115 contact 18 for each switch blade. The contacts 18 are electrically connected with the fuse clips 15 preferably by means of bolts 20 which extend through the board 14 to hold the fuse clips and contact members in 120 position. The fuse clips 16 are carried by plates 21 to which the branch line terminals 22 may be connected as clearly shown in Fig. 4.

125 The switch blades 19 are supported in an elongated carrier 23. This carrier is pivoted to rock about its longitudinal axis, suitable extensions 24 being provided at its opposite ends to engage within bearings formed in supporting plates 25. The blades 130

are spaced apart along the length of the carrier and project laterally therefrom. They are insulated from each other as by means of the insulating strips 26. The 5 blades are double ended so in "on" position their opposite ends simultaneously engage the bus bars 1 and the contact members 18 respectively.

The supporting plates 25 are carried by 10 the board 14 by means of bracket plates 27. These plates 27 are arranged one at each edge of the board and at right angles to the plane of the board. They are fixed to the board by means of bolts or rivets 28 15 which extend through the board and through portions 29 of the plates which are bent at right angles and rest against the forward surface of the board. The supporting plates 25 are riveted, or otherwise secured to the inner surfaces of the plates 27 and extend 20 forwardly beyond the board 14 as clearly indicated.

Of course, it will be understood that any other suitable means may be employed for 25 connecting the supporting plates 25 with the board 14. The only requirement in this connection is that the supporting plates and all of the parts carried thereby shall be in turn carried by the board 14 so as 30 to be bodily insertible into the stall, and bodily removable from the stall with the board 14. The board 14 may be considered as a frame or carrier for the switch mechanism, contacts, and fuse clips, by means of 35 which all of said parts may be readily arranged in proper coöperative position with the bus bars.

When moving a switch unit into position 40 within a stall it is simply necessary to rest the board upon the horizontal partition 13 forming the bottom wall of the stall and then to move it inwardly until the upper and lower portions of its forward face engage against cross members 30. Attaching 45 screws 31 are then inserted through suitable apertures 33 formed in the cross members 30.

These cross members 30 are fixed at their outer ends to the walls 4 and at their inner 50 ends to the central partition 12 and they are sufficiently wide so as to project above and below the adjacent horizontal partitions 13.

The position of the cross members 30 is 55 such, with respect to the rear surface of the face plate L, as to properly and positively determine the position of the forward face of the board 14 with respect to the bus bars 1 when the boards are moved 60 home against said cross members. The switch blades and the contacts 18 are likewise properly positioned by the cross members at the same time.

The cross members may be formed integrally with the horizontal partitions 13, if

desired, but preferably they are formed as separate elements and are connected together by means of an angle bracket 34. The rear edges of the horizontal partitions 13 are preferably turned downwardly as 70 at 35 to form suitable abutments for the doors G, and are supported from the walls 4 and the central partition by angle brackets 36.

Preferably the horizontal partitions 13 75 are arranged at somewhat of an incline, as clearly shown in Fig. 4, so as not to be serviceable for supporting foreign parts which may be carelessly laid thereon unintentionally. Short circuiting of any of 80 the current-carrying parts is thus guarded against.

In order to provide passage for the branch line wires through the walls 4 into the respective stalls, portions of said walls 4 are 85 cut away at each stall to provide openings 37 in convenient positions adjacent the terminal plates 21. The openings 37 are preferably cut entirely through the flanges 8 of the walls 4, as clearly seen in Fig. 4 in 90 order that, after removing the walls 5, the branch line wires may be readily swung backwardly out of the openings, thus facilitating the operation of applying the terminal members 22, or for other purposes. 95

The upper and lower edges of the openings 37 are fitted with curved guard members 38 so as to prevent likelihood of abrasion of the wires.

The construction of the switch mechanism, 100 and its manner of control, includes a bell-crank which is pivotally mounted, as at 39, upon the outer supporting plate 25. This bell-crank is preferably made up of two plates, as 40 and 41, spaced apart. At the 105 end of one of the arms a link 42 is pivotally mounted between the plates 40 and 41 and extends into pivotal connection with the switch blade carrier 23, the point of connection with the switch blade carrier being at 110 one side of the pivotal axis, as at 43. The bell-crank and the link 42 constitute a toggle by means of which to swing the switch blades to "on" and "off" positions.

An operating rod 44 extends between the 115 plates 40 and 41 and has slot connection with a cross pin 45 at the remaining end of the bell-crank. This operating rod extends forwardly through an opening 46 formed in the face plate L and is pivotally connected, 120 as at 47, to an operating handle 48. The operating handle is pivotally mounted, at a point spaced from the pivot 47, as at 49, so as to serve as a crank to move the rod backwardly and forwardly when the operating 125 handle is swung.

Thus when the operating handle is moved into a vertical or "on" position, the rod 44 swings the bell-crank and straightens the toggle so as to hold the switch blade "on" as 130

shown in Fig. 4. On the other hand, when the handle is thrown down into "off" position, the rod 44 is moved backwardly so that the end wall 50 of its slot engages the cross pin 45 and swings the bell-crank to break the toggle and permit the switch blade to snap into the "off" position as shown in Fig. 5.

A coil spring 51 is arranged at the opposite end of the carrier, in engagement between the carrier and the adjacent supporting plate 25 so as to exert a continual tendency to move the carrier into the "off" position, the slot in the rod 44 providing for an unobstructed movement of the toggle into "off" position once the toggle is broken.

In order to prevent the guard member or door G from being opened while the switch is "on" said door is preferably mounted on hinges 52 adjacent the rear edge of the wall 4 and a link 53 is pivotally connected thereto as by a pin 54 carried by a stud 55 fixed to the door. The stud supports the pin 54 at a point removed from the axis of the hinge. This link is shaped substantially as shown in Fig. 11 and at its inner end it carries a lug 56 which slides backwardly and forwardly along a slot 57 formed in the adjacent plate 25 whenever the door is opened or closed. A transverse head 58 is formed at the outer end of the lug to prevent accidental detachment of the lug from the slot. The plate 41 of the bell-crank above described is enlarged and is provided with an arcuate slot 59 through which the lug 56 extends, the plate 41 being interposed between the plate 25 and the link 53. One end of the slot 59 terminates in a radial extension slot 60. When the bell-crank is in the "on" position, the lug 56 stands at one end of the arcuate slot 59 and the engagement of the walls of this slot with the lug prevents the lug from moving outwardly along the slot 57, and thus, of course, prevents the door from being opened. So long as the door is closed the bell-crank may be swung freely, the lug being accommodated by the arcuate slot. When the bell-crank is in the "off" position the extension slot 60 will stand in parallelism with the slot 57, and the door may then be opened at will, the lug 56 traveling along the length of the two slots, as clearly shown in Figs. 5 and 6.

After the lug 56 has moved into the slot 60, said lug serves as a positive stop against return rotation of the plate 41, thus locking the switch mechanism in the "off" position whenever the door is open.

The free edges of the sets of doors at opposite sides of the central partition 12 are separated by an extension strip 61 which preferably projects outwardly from between said doors a sufficient distance to allow a slight opening movement of the door without giving access into the space behind the

door. This will take care of any inaccuracies, or looseness offered between the parts connecting the door with the switch mechanism and will insure an "off" position of the switch mechanism before any access is given.

As a simple means for giving required stiffness to the central partition, and of providing the extension 61 and of providing stops 62 for the free edge of the door, said partition is preferably made of a pair of plates spaced apart with the strip 61 fixed between their rear edges. The forward edges are spaced away from the rear surface of the face plate so as to provide for a free circulation of air from one side of the central partition to the other and said rear edges are connected to the face plate by means of a series of rods or bars 63 which have a portion 64 extending between and fixed to the partition plates.

The horizontal partitions 13 likewise are spaced away from the rear surface of the face plate so as to provide for a free circulation of air vertically from one switch mechanism to the other.

It will be seen that by means of this construction the rear surface of the face plate is divided off into a number of well ventilated stalls, each having its independently operable, independently attached, and independently removable switch unit, that each stall is guarded by an independent guard member, and that each switch unit includes a barrier spaced back of the door providing a safe fuse compartment and a guarded switch compartment, that the door to the fuse compartment may not be opened except when the fuse terminals are dead, and that the switch may not be moved to the "on" position to render the fuse terminals live except when the door is closed.

When it is desired to remove one of the switch units it is simply required to throw the switch off, open the door, remove the screws 31 and disconnect the link 53 and rod 44 from the door and switch handle, and then lift the switch unit away where it may be conveniently operated upon to any extent and then as readily returned.

The operating rod 44 preferably moves through a supporting member 65 provided upon the plate 25, and the object of this supporting member is to retain the rod in a substantially horizontal position when the switch unit is detached, as shown in Fig. 2, thus facilitating the proper and easy entrance of the rod into the aperture 46 of the face plate L when moving the switch unit into a stall.

The link 53 may be disconnected from the door by simply lifting out the pin 54 which is preferably provided with a removable cotter pin 66 for this purpose. When the link drops downwardly into a vertical position its head 58 will then register with the slot

57 and may be readily disconnected if desired.

The operating rod 44 may be easily disconnected from the switch handle 48 in the 5 manner suggested in Figs. 12 and 13. This includes first the removal of the pivot pin 49 thus allowing the operating handle to drop so that the pivot pin 47 falls below the lower edge of the bracket plate 67. The 10 pivot pin 47 may then be readily slid out. Until the pivot pin 49 was withdrawn the pivot pin 47 was held against displacement by the opposing bracket plates between which it moved.

15 It will be apparent also that the branch line wires may lead into the channels 3 at any point along the length of the walls 5 or they may lead into the channels 3 directly into the top or bottom ends of said channels.

20 The main line wires may likewise lead into connection with the bus bars either from above or below or from either side. Preferably connecting bus bars 68 are provided at either the upper or lower ends of the main 25 bus bars for connecting the two sets of bus bars together, and the main line wires lead into connection with these connecting bus bars from any direction.

When it is desired to provide a very large 30 switch board several of the sections shown in Fig. 1 may be set side by side and connected together as suggested by the sectional view of Fig. 14. In making the connection the outer wall members 5 of the channels 3 are removed and a single cover plate 69 35 bridges between the adjacent plates 4, thus making an attractive and substantial connection between the sections and at the same time providing a double size channel for 40 the branch line wires which now will lead therealong and in the opposite directions to the adjacent stalls at opposite sides of the channel. The brackets 6 to which the walls 5 are connected are now connected together 45 by bolts 70.

The guard doors G for all of the sections may be fitted with spring catches 71 arranged to engage within openings 72 formed in the strip 61.

50 In the modification Fig. 15 a simple expedient is illustrated by means of which the contacts 18 at the rear face of the board 14, and the plates for carrying the fuse clips 15 may be made as an integral element instead 55 of depending upon the bolts (as 20 in Fig. 4) for electrical connection. This includes making the contact members and the plates from a strip of material bent into Z-shape and passed through an opening formed in 60 the board 14 as clearly indicated.

Having thus described my invention, what I claim as new and desire to secure by Letters Patent is:—

1. A switch board made up of a plurality 65 of independent board sections connected to-

gether, each section having independently operable mechanism carried thereby, and the sections being shaped to provide wire channels between them along which leading-in wires may pass to the respective 70 mechanisms.

2. A switch board made up of a plurality of independent board sections connected together, and means connecting said sections together providing inclosed wire channels 75 between the sections.

3. A panel board having a plurality of mechanisms mounted thereon, means carried by the board forming an inclosure for said mechanisms, parts also carried by the 80 board providing inclosed wire channels at opposite sides of the said mentioned inclosure, said board being adapted to be assembled with other similar boards arranged edge to edge, and said last mentioned parts 85 of adjacent wire channels of abutting boards being removable to provide a common wire channel of increased size between the abutting boards, together with a separate member adapted for connecting together said 90 abutting boards and for closing said enlarged wire channel.

4. A switch board structure comprising in combination a base board, means forming a plurality of independent stalls at one 95 side of the base board, a plurality of independently formed and independently operable switch units removably contained one within each of said stalls, and a bus bar traversing said stalls with which the switch 100 mechanisms directly coöperate.

5. A switch board structure comprising in combination a base board, a plurality of switch units carried by the base board, each of said switch units comprising fuse clips, 105 switch blades and switch blade operating mechanism all constructed as an entity and being bodily attachable and removable from the base board, means providing stalls upon the base board to receive said switch units, 110 and means providing wire channels communicating with said stalls.

6. A switch board comprising a base board, a plurality of switch units carried by the base board, each of said switch units comprising fuse clips, switch blades and switch blade operating mechanism all constructed as an entity and being bodily attachable and removable from the base board, bus bars carried by the base board, 115 means defining an inclosure within which all of said switch units are contained, and means within said inclosure supporting the switch units with the switch blades thereof in coöoperative relation with said bus bars. 120

7. A switch board comprising a base board, a plurality of switch units carried by the base board, each of said switch units comprising fuse clips, switch blades and switch blade operating mechanism all con- 130

structed as an entity and being bodily attachable and removable from the base board, bus bars carried by the base board, means defining an inclosure within which all of 5 said switch units are contained, means defining stalls within the inclosure one for each switch unit, and the parts defining said stalls being spaced away from the surface of the base board so as to permit free 10 circulation of air within the inclosure over the surface of the base board.

8. A switch board comprising a base board, a plurality of switch units carried by the base board, each of said switch units 15 comprising fuse clips, switch blades and switch blade operating mechanism all constructed as an entity and being bodily attachable and removable from the base board, means defining an inclosure upon the 20 base board within which said switch units are contained, means dividing the inclosure into stalls one for each switch unit, and the inclosure including an independently operable guard door for each stall.

25 9. A switch board comprising a base board, a plurality of switch units carried by the base board, each of said switch units comprising fuse clips, switch blades and switch blade operating mechanism all constructed as an entity and being bodily attachable and removable from the base board, means defining an inclosure upon the base board within which all of said switch units are contained, cross partitions within the 30 inclosure dividing the inclosure into a plurality of stalls one for each switch unit, a guard door for each stall, and one of said partitions comprising a common abutment member for said doors.

40 10. A switch board comprising a base board, a plurality of switch units carried by the base board, each of said switch units comprising fuse clips, switch blades and switch blade operating mechanism all constructed as an entity and being bodily attachable and removable from the base board, means defining an inclosure upon the base board within which all of said switch units are contained, vertical and 45 horizontal partitions arranged within said inclosure dividing the inclosure into a plurality of stalls one for each switch unit, the inclosure including doors for said stalls, and the horizontal partitions being arranged at 50 an incline for the purpose described.

55 11. A switch board made up of a plurality of independent board sections connected together, two abutting board sections each having a series of independently operable 60 switch mechanisms spaced apart along the length of the joint between the two board sections, each of said two board sections also having means defining a wire-receiving space extending along the length of its respective series of switch mechanisms along

which space wires may pass to the respective switch mechanisms, and said space of said two mentioned abutting board sections being shaped to coöperate with each other to provide a common enlarged wire channel 70 between the two mentioned abutting board sections.

12. A switch board made of a base board, conductors mounted in close proximity to one side of said base board, means forming 75 a plurality of independent stalls at the same side of the base board, a plurality of independently operable switch units one for each of said stalls, each including a switch blade movable into and out of engagement 80 with the conductor for deriving current therefrom, and supporting means for supporting the switch units within the stalls, said supporting means being of a character to permit ready attachment and removal of 85 the switch units into and out of position enabling engagement of the conductor by the switch blade.

13. A switch board comprising a base board, a bus bar supported and fixed to one 90 surface of the base board, means forming a plurality of independent compartments upon the same surface of the base board and extending side by side along the bus bar so that the bus bar traverses all of the compartments, a plurality of switch units one for each compartment, and means for removably supporting the switch units in the compartments in positions wherein they are adapted for "making" and "breaking" 10 electrical connection with the portions of the bus bar traversing the respective compartments.

14. A switch board comprising a base 10 board, a bus bar extending along one surface of the base board, means defining a plurality of independent compartments along the length of the bus bar so that the bus bar traverses all of said compartments, 11 a plurality of independent switch units one for each compartment adapted for deriving current from the portions of the bus bar traversing the respective compartments, means defining the compartments upon the 11 base board constituting supports for the switch units, and means whereby the switch units are readily attachable to and removable from said supports.

15. A switch board comprising a plurality 12 of independent board sections connected together, each board section having independently operable mechanism carried thereby, adjacent portions of two abutting board sections being shaped to provide a wire channel 12 between them, and a member forming a part of the wire channel serving to hold the two board sections together.

16. A switch board comprising a base board, a group of switch units at one side of 13

the base board, each comprising fuse clips, a switch blade, and switch blade operating mechanism all constructed to be handled as an entity, means forming wire channels 5 upon the base board at opposite sides of said group of switch units, shelves extending between said wire channel forming means, said shelves constituting supports for the switch units, and means whereby the switch units 10 are bodily attachable to and removable from said shelves.

17. A switch board comprising a base board, a bus bar extending along one surface of the base board, a group of switch units at 15 one side of the base board each comprising fuse clips, a switch blade, and switch blade operating mechanism all constructed to be handled as an entity, means forming wire channels upon the base board at opposite 20 sides of said group of switch units, shelves extending between said wire channel forming means, said shelves constituting supports for the switch units, and means whereby the switch units are bodily attachable to 25 and removable from said shelves at will, said shelves being disposed so as to support the switch units with the switches thereon in co-operative relation with the adjacent portions of the bus bar.

30 18. A safety switch board comprising a plurality of fuse clip supporting plates, fuse clips carried by said plates at one side thereof, switch contacts electrically connected with said fuse clips, a plurality of switches 35 one for each of said plates operable to move into and out of engagement with the switch contacts, bus bars extending common to said switches, means to operate said switches, a guard wall standing to guard 40 said fuse clips collectively, said guard wall comprising a plurality of displaceable doors one for each of said fuse clips supporting plates, said switch contacts and switches being mounted upon the respective fuse clips supporting plates to be handled as an entity therewith, and means whereby said entities are individually removably mounted.

19. A safety switch board mechanism including a plurality of switches, a protecting wall for said switches comprising a plurality of independently displaceable doors one for each of said switches, fuse retaining parts associated with said switches, supporting means for said fuse retaining parts spaced behind said doors and arranged to support said fuse retaining parts in a position of accessibility when the respective doors are open, said supporting means being 50 arranged intermediate the fuse retaining parts and the respective switches and being of a character to guard the switches when the doors are displaced, and holding means 55 removably retaining said supporting means 60 in position, said holding means being in-

accessible except when the doors are displaced.

20. A safety switch board mechanism including a plurality of switches, a protecting wall for said switches, comprising a plurality of independently displaceable doors one for each of said switches, conductors extending common to said switches, fuse retaining parts and branch line contacts associated with said switches, supporting means 70 for said fuse retaining parts and branch line contacts arranged intermediate said doors and said switches and supporting said fuse supporting parts at its side adjacent the door and supporting said branch line 75 contacts at its side remote from the door, said supporting means constituting barriers between the doors and the switches, and said supporting means constituting also together with the switches, the fuse retaining parts 80 and the branch line contacts a single entity 85 removably supported.

21. A switch board comprising a supporting member, means carried by the supporting member defining a plurality of independent casings upon one side of the supporting member, a plurality of independent switch units one for each casing, means for independently removably supporting the switch units within the respective casings, 90 each switch unit comprising a movable switch blade, independent operating means for the switch blades extending exteriorly of the respective casings, and a bus bar traversing said casings having portions spaced 95 apart in its length and exposed to said switch blades with which the switch blades co-operate for closing a circuit including the bus bar and the switch blades.

22. A switch board comprising a supporting member, means carried by the supporting member defining a plurality of independent casings upon one side of the supporting member, a plurality of independently removable switch units one for each casing, 100 means extending exteriorly of the respective casings for actuating the respective switch units, and a bus bar traversing said casings having portions spaced apart in its length 105 and exposed within the respective casings with which the switch mechanisms are 110 adapted to co-operate.

23. A switch board comprising a supporting member, means connected with the supporting member defining a plurality of independent casings at one side of the supporting member, a plurality of independently removable switch units one for each casing, each switch unit having a part adapted 115 when in position within the casing to divide 120 the casing into a switch compartment and a fuse compartment.

24. A switch board comprising a supporting member, means connected with the supporting member defining a plurality of inde- 130

pendent casings at one side of the supporting member, a plurality of independently removable switch units one for each casing, each switch unit having a part adapted

5 when in position within the casing to serve as a partition member for dividing the casing into two compartments, each switch unit comprising also a switch mechanism supported at one side of said partition member

10 adapted to stand within one of said compartments and comprising fuse clips supported at the opposite side of said partition member adapted to stand within the other compartment, together with operating

15 means for the respective switch mechanisms.

25. A switch board comprising a supporting members, means connected with the supporting member defining a plurality of independent casings at one side of the supporting member, a plurality of independently removable switch units one for each casing, each switch unit being of a character such that when in position within the casing it will divide the casing into two compartments containing different parts of the switch unit.

26. A switch board comprising a base board, a pair of wall members carried by the base board, projecting at right angles from

30 the surface thereof adjacent the opposite marginal edges of the base board, a third wall member arranged between said two mentioned wall members, substantially parallel thereto and at right angles to the mentioned surface of the base board to divide the space between said two mentioned wall members into two compartments, two sets of bus bars carried at the mentioned surface of the base board also extending substantially parallel to the first two mentioned walls, one set in each of said compartments, a plurality of switch mechanisms in each compartment spaced apart along the length of the respective bus bars, and means providing inclosed branch line wire channels beyond said first two mentioned walls along which channels branch line wires may lead into connection with the respective switch mechanisms through openings formed in

50 said first two mentioned walls.

27. A switch board comprising a base board, a plurality of switch units carried by the base board, each of said switch units comprising fuse clips, switch blades and

55 switch blade operating mechanism all constructed as an entity and being bodily attachable and removable from the base board, bus bars carried by the base board, and means to support said switch units with the switch blades thereof in coöperative relation with said bus bars.

28. A switch board comprising a base board, a plurality of switch units carried by the base board, each of said switch units

60 comprising fuse clips, switch blades and

switch blade operating mechanism all constructed as an entity and being bodily attachable and removable from the base board, bus bars carried by the base board, means defining a plurality of stalls upon the base

70 board one for each switch unit, and said stalls including parts to which the switch units are directly connected, said parts being adapted to support the switch units with the switch blades of said units in proper coöperative relation with the bus bars.

29. A switch board comprising a base board, a plurality of switch units carried by the base board, at one side thereof, means supporting the switch units in position, a

80 switch operating handle arranged at the opposite side of the base board for one of said switch units, said switch unit including a connecting rod which extends through an opening in the base board to said operating handle, means whereby said switch unit is bodily attachable and removable from its supporting means, and said switch unit including further means for supporting the connecting rod in a position to readily enter the opening

85 through the base board as said switch unit is being moved into connection with its supporting means.

30. A switch board comprising a base board, live contact members carried at one

90 surface thereof, means defining an inclosure for said live contact members, said means including a guard door, a barrier supported parallel with the base board spaced therefrom between the live contact members and the door so as to protect the live contact members when the door is open, fuse clips arranged between the barrier and the door being readily accessible when the door is open, a switch mechanism arranged between

95 the barrier and the contact members being electrically connected with the fuse clips and being adapted to coöperate with the bus bars, and operating means for the switch mechanism extending to the opposite side of

100 the base board.

31. A switch board comprising a base board, live contact members carried at one surface thereof, means defining an inclosure for said live contact members, said

115 means including a guard door, a barrier supported parallel with the base board spaced therefrom between the live contact members and the door so as to protect the live contact members when the door is open, fuse clips supported upon the face of the barrier between the barrier and the door and being readily accessible when the door is open, a switch mechanism supported by the barrier between the barrier and the contact members being electrically connected through the barrier with the fuse clips, operating means for the switch mechanism, and means whereby the barrier with its

120 fuse clips and switch mechanism may be

125

130

bodily removed as an entity from said inclosure.

32. A switch board comprising a base board, bus bars arranged at one side thereof, means defining an inclosure for said bus bars, a plurality of switch units arranged within the inclosure to coöperate with the bus bars, means also within the inclosure dividing the same into a plurality of stalls one for each switch unit, the means defining the inclosure including a door for one of said stalls, the switch unit within said mentioned stall comprising a barrier supported parallel with the base board spaced therefrom between the bus bars and the door so as to protect the bus bars when the door is open, fuse clips supported upon the face of the barrier between the barrier and the door and readily accessible when the door is open, a switch mechanism supported by the barrier between the barrier and the bus bars being electrically connected through the barrier with the fuse clips, operating means for the switch mechanism, and means whereby said switch unit may be bodily removed as an entity from said stall.

33. A switch board comprising a base board, bus bars carried by the base board at the rear side thereof, a plurality of independently formed and independently operable switch units supported by the base board at the rear side thereof for coöperating with said bus bars, switch handles supported at the front side of the base board, operating means for said switch units extending through openings formed in the base board into connection with said switch handles, means whereby the operating means may be disconnected from the

switch handles, and means whereby the switch units may be thereafter bodily disconnected from the base board.

34. A switch board comprising a base board, a switch unit carried by the base board comprising a plate, a switch blade carried by the plate at one face thereof, fuse supporting means carried by the plate at the opposite face thereof, and operating mechanism for the switch blade, said plate, said fuse supporting means, said switch blade, and said operating mechanism being all constructed as an entity and being bodily attachable and removable from the base board.

35. A switch board comprising a base board and a switch unit, said switch unit comprising a plate, comprising also a switch blade carried by the plate at one face thereof, and comprising also fuse supporting means carried by the plate at the opposite face thereof, the base board having means providing an open-sided inclosure thereon to receive the switch unit, said inclosure forming means having parts to receive and support said plate, retaining means connecting the plate within said inclosure forming means in position to constitute a barrier between the switch blade and the open side of said inclosure, and the retaining means being releasable to render the plate and the parts carried thereby constituting the switch unit bodily removable from the inclosure.

In testimony whereof I affix my signature 75 in the presence of two witnesses.

HUBERT F. KRANTZ.
